ANTOINE VÉRIGEL, OF BALDWIN, NEW YORK, ASSIGNOR TO DOEHLER PRODUCTS CORP.,
A CORPORATION OF NEW YORK

METAL FURNITURE

Application filed July 26, 1926. Serial No. 124,946.

My invention has particular reference to metal furniture, one of the objects being to make it possible to ship such furniture in a "knocked down" or disassembled state and to provide for the ready assembling of the several sections of the articles of furniture in such a manner that they will be firm and rigid, and at the same time may be quickly disassembled, if desired.

10 - The more common practice among manufacturers of metal furniture at the present time is to assemble the sections of each unit of metal furniture at the factory, usually in a permanent form, as, for example, by welding. While this practice has the advantage of providing the desired rigidity to the article of furniture, it has the obvious disadvantage of requiring an undue amount of space in shipment and also has the further disadvantage of making it impossible for the user of the furniture to replace an injured part.

Because of the recognition of these disadvantages, manufacturers have to some extent adopted the practice of making sectional furniture in such a way that it may be readily assembled or disassembled. The usual securing means for the sections in such cases are rivets or bolts, but these have not proven altogether satisfactory for the reason that they soon become loose, and for the further reason that they draw the sections together in only one direction, and therefore, it is not possible in many cases to obtain the tight joints which are required both for sightliness and for rigidity.

In accordance with my invention I have provided an improved form of means for securing the sections of furniture together, which not only have the desirable quality of easy and convenient operation in assembling and disassembling the sections, but have the further advantage that they lock the parts together with sufficient rigidity, without any possibility of the joints becoming loosened by use. These advantages are obtained from what I term the "wedge-cam" construction which characterizes my invention. My invention is well adapted for application to joint constructions in which one section both abuts against and is partially overlapped by

its adjacent section so that there are two angular faces of abutment or contact to the joint, and, as the term "wedge-cam" implies, a feature of my invention is the fact that by a simple manipulation of a cam, co-acting 55 wedges may be caused to draw the sections together in the two directions which are respectively normal to the two angular faces.

In the form of my invention which I employ at present, the wedging action is obtained by co-acting wedge sockets and plugs whose axes are inclined in the two desired directions with respect to the direction of relative movement of the sections for assembly and disassembly, and to which relative 65 movement is imparted by a co-acting cam and lug, the cam assuming a locked position with respect to the lug at the conclusion of the wedging movement.

The walls of the furniture which is of an enclosing type, such as cabinets, dressers, desks, and the like are, as a general rule, made from sheet metal, and the plugs in such case may be semi-conically rolled extremities of lateral extensions on the sheet metal, 70 while the sockets are also of semi-conical shape and disposed on the inner faces of frame parts which form the legs or other solid supporting parts. Obviously these may be reversed in location. The lug with which the cam cooperates may also be formed by the folding of a lateral extension on each plug-carrying sheet metal section. In such case the cooperative cam will be on the support, and when rotated will engage with the 75 lug and force the plugs into the sockets, thereby drawing the section in the two directions of inclination of the socket and effecting a 80 tight joint.

The normal size of the plug will be preferably slightly larger than the inner diameter of the socket, but its resilient nature will permit it to become smaller in diameter to the necessary extent as it is forced by the cam action to its final position in the socket. The 85 resultant expansive tendency of the plug in the socket holds the joint very tightly against strains, and yet, because of the resilient character of the union, it will be appreciated that the strains will be absorbed without the wear 90 100

that is incident to rivet and bolt constructions. The long bearing surfaces of the wedge sockets and plugs render the joints very firm and strong.

5 These joining and locking means have the further advantage that they require no parts additional to those carried by the sections themselves to secure the sections together, as will appear from the detailed construction of the illustrated embodiment of my invention.

10 Certain other details of construction which are also comprehended within my invention, will likewise appear from the description hereinafter.

15 I shall now describe the embodiment of my invention illustrated in the accompanying drawings, and shall thereafter point out my invention in claims.

20 Fig. 1 is a front elevation of an article of furniture embodying this invention;

Fig. 2 is an enlarged horizontal section taken along the section line 2—2 of Fig. 1;

25 Fig. 3 is an enlarged detail of a fragmentary portion of the article at the left near the top as viewed in Fig. 1;

Fig. 4 is a vertical section taken along line 4—4 of Fig. 3;

Fig. 5 is a vertical section on line 5—5 of Fig. 1;

30 Fig. 6 is an enlarged vertical section of the upper portion of the article, as indicated by line 6—6 of Fig. 5;

Fig. 7 is an enlarged sectional detail on line 7—7 of Fig. 5;

35 Fig. 8 is a detail view corresponding to the right and middle in Fig. 5, showing adjacent portions of two sections in a preliminary stage of assembly;

Fig. 9 shows a suitable operating tool for the cam.

40 For the purpose of illustration I have shown my invention as embodied in a sectional metal dresser having the customary mirror 1 supported by two arms 2 secured to the chest portion of the dresser in any convenient manner.

45 The chest portion of the dresser is supported as usual upon four legs which form corner pieces and additionally is made up of seven sections including a top and bottom, two side or end pieces, a back and two drawer frames. The legs are rigid, angle metal members formed conveniently and economically by die-casting. The front legs or corner posts are numbered 3 in the drawings and the similar rear legs (only one of which is shown) are numbered 4. The other sections are stamped from sheet material. The two side members 5 (only one of which appears in the drawings), back member 6 and the two drawer frames 7 and 8 are attached to the legs, which form corner frame pieces, by the wedge-cam construction which is above referred to, and which will be presently described.

50 The top 9 is given the appearance of thick-

ness by hollow edge strips 9a along the front and sides secured on the under side of the flat metal plate, as is usual in such constructions, and each of the side edge strips 9a is hinged to its side member 5 by a hinge 5a, formed by rolling the two overlapping edges concentrically, as shown in Fig. 6, thereby permanently securing the top to the side members while making it possible to fold them flat for shipment. The bottom 10 is similarly hinged by the roll hinge 10a to the rear or back member 6. The bottom 10 is releasably secured at its front edge to the bottom flange of the lower drawer frame 8, as by a button 11.

55 The wedges in the construction shown are in the form of taper or semi-conical rigid sockets 12 which are cast on the inner faces of the rigid corner frame pieces or uprights which also form the legs, and cooperative plugs 13 which are similarly tapered are formed by rolling to semi-conical shape the extremities of lateral extensions 14 on the several sheet metal sections which are directly attached to the corner frame pieces. As shown in Fig. 2, as well as clearly indicated in Figs. 4, 5 and 8, each sheet metal member on which plugs are formed has each vertical edge offset so as to form an angle providing a groove within which the corner of the leg fits. Also, as clearly shown in the drawings, the edge of each leg member is formed with an inner groove into which fits the outer corner formed by the offsetting of the sheet metal member. Thus there is formed a double lap joint having three abutting surfaces. The lateral extensions 14 overlap the inner face of the leg for a little distance, and then are rolled in the semi-conical form to provide the tapered plugs 13 for insertion in the sockets 12. Each leg is an angle member and has a series of sockets cast on each of its inner angular faces. The axis of each socket is inclined to each face of the angle formed by the sheet metal member within which the corner of the leg fits, being shown as diverging downwardly from these faces, and the axis of the plug has a similar inclination. Consequently as the plugs are forced down into their sockets, the section of which they form a part is forced toward the leg in the two directions normal to the faces of the angle. Thereby the three angularly joined flat surfaces on the sheet metal section, formed by its offsetting, are drawn into firm engagement with the three complementary flat angularly joined surfaces on the leg member, formed by its groove and outer flange.

60 The semi-conical ends on the extensions 14 which constitute the plugs 13 are normally of a somewhat larger size than the inside of the rigid sockets 12, and as these plugs are forced into the sockets they are curled up to the smaller size required, their circumferential length being such as to permit of this. The resilient expansive force of the plugs there-

fore causes them to fit very snugly into the sockets and will hold the joints tightly and firmly. Ordinary strains, such as tend to enlarge rivet holes, will be absorbed by the plugs because of their resilient character.

5 To force the plugs into the sockets I provide a cam construction which will now be described. On each inner face of each leg is 10 rotatively mounted a cam 15 between two of the sockets 12, the cam face being approximately a parabolic curve. Cooperative with each cam is a lug 16 on the adjacent edge of the sheet metal member adjacent to the face of the leg. This lug is a lateral extension on 15 the sheet metal section folded to channel shape so as to slide over the cam as the sheet metal section is slid down over the face of the leg in entering the plugs 13 into the sockets 12. This preliminary position is represented in Fig. 8. The parts are so disposed that when the plugs have been entered into the sockets as far as they will easily go, the channel abutment or lug 16 will have passed over the cam 15, and the cam is then free to 20 be rotated to complete the wedging action and the securing of the joint. The cam may be operated in any convenient way. It is shown as being provided with a square socket for the reception of any suitable tool, such, for example, as is shown in Fig. 9. At the conclusion of the camming action, a projecting finger 15a on the cam strikes against the wall of the abutment 16 and the cam is thus locked in position, against overthrow. In this way 25 the joint itself is securely locked and can only be released by the backward rotation of the cam 15.

The illustrated dresser has a bottom drawer 17, a middle drawer 18 and two top drawers 40 19 and 20 disposed side by side. To accommodate these drawers there are provided the two drawer frames 7 and 8 above referred to. These drawer frames are stamped from sheet metal and span the two front legs. The lower frame 8 has a full length opening to accommodate the drawer 17 of full width. The upper drawer frame 7 has two half-width openings to accommodate the two half-width drawers 19 and 20. Suitable runners or guides 45 21 on the side sections 5 (see Fig. 5) serve to support and guide the drawers. There will also be a suitable runner or guide which is not shown in the drawings for the inner sides of the drawers 19 and 20, extending from the drawer frame 7 to the back section 6.

The drawer frames are flanged on all four sides as appears more clearly from Figs. 2 and 5. The middle drawer 18 will slide on top of the drawer frame 8. For attachment of 50 these drawer frames, each front leg has on the inner face of its front portion four properly spaced double taper inclined sockets 12 as above described, two for each end of each drawer frame, and between these sockets it has the rotative cam 15; while each end of

each drawer frame has its edge inwardly offset, as above described, and provided with two double taper inclined plugs properly positioned to fit within the sockets, and with the channel shape cam abutment 16 between the two plugs in proper position to be engaged by the cam. Obviously the number of wedge sockets and plugs is optional. 70

The side sections 5 are similarly connected at their fronts to the other angle face of the 75 respective front legs 3, while their rear edges are similarly connected to the inner side faces of the rear angle legs 4, as shown in Fig. 5. For this purpose I have shown four wedge sockets and plugs on each edge, and an abutment for the cam between the two middle sockets and plugs. Here again the number of wedges is optional. 80

The rear section 6 is similarly connected by my wedge-cam joint to the inner rear faces 85 of the two rear legs 4, four wedges and a single cam being shown therefor in connection with each rear leg.

It will be appreciated that the several sections of the illustrated article of furniture 90 may be compactly shipped and may be very quickly assembled and disassembled. The joints have no tendency to become loosened, even after prolonged usage. Ordinary shocks to which furniture is subjected are absorbed 95 at the joint without wear, and there is at all times a resilient strain holding the joint together. Practically the joint is altogether firm and rigid.

It is obvious that various modifications may 100 be made in the construction shown in the drawings and above particularly described, within the principle and scope of my invention.

I claim:

1. In combination, two separate metal furniture parts to be detachably connected together, one of said parts having a straight groove with flaring surfaces provided along an edge thereof and the other said part having a corner along an edge thereof providing converging surfaces complementary to the flaring surfaces of the groove to fit therein, and coacting wedge members carried respectively by the said parts to operate upon relative sliding movement of the said edges to draw them together in a direction to cause a firm abutting relation between the two surfaces of the groove and the two complementary surfaces of the corner so that thereby 110 the two said parts are firmly connected together against relative movement other than a reverse sliding movement by which they may be separated. 115

2. In sectional furniture, the combination 120 of a rigid metal frame piece provided along an edge thereof with a straight substantially right angular corner at its inner side, a sheet metal section bent to be offset inwardly along a margin thereof to provide a straight sub- 125

stantially right angular groove which is complementary to the said corner, a wedge member on the frame piece at its inner side having a wedging surface inclined with respect to the frame edge, and a cooperating complementary wedge member on the inner offset edge portion of the sheet metal section for thereby firmly diagonally drawing together the said angular corner edge and the said 10 complementary angular grooved edge upon relative sliding movement of the said edges.

3. In sectional furniture, the combination of a rigid metal frame piece provided along one edge at the inner side thereof with a substantially right angular groove forming an inner substantially right angular corner, a sheet metal section offset inwardly along a margin thereof to provide on the outer side of its margin a corner and a groove which are 15 complementary respectively with the said groove and inner corner of the frame piece so as to have interfitting abutting relation therewith, with the outer edge margin of the frame piece overlapping upon the outer side 20 of the sheet metal section and with the offset inner edge margin of the latter overlapping upon the inner side of the frame piece, a wedge member on the inner side of the frame piece with its wedging surface directed diagonally towards the inner side of the frame piece and away from its grooved corner edge, and a cooperating wedge member carried by the inner offset margin of the sheet metal section with a similarly inclined wedge surface 25 complementary to that of the wedge member on the frame piece so that thereby upon relative sliding movement the cooperating wedge members will draw the said angular corners into the said respective complementary grooves in firm abutting relation.

4. In sectional furniture, the combination of a rigid metal frame piece provided along one edge at the inner side thereof with a substantially right angular groove forming an inner substantially right angular corner, a sheet metal section offset inwardly along a margin thereof to provide on the outer side of its margin a corner and a groove which are complementary respectively with the said groove and inner corner of the frame piece so as to have interfitting abutting relation therewith, with the outer edge margin of the frame piece overlapping upon the outer side of the sheet metal section and with the offset inner edge margin of the latter overlapping upon the inner side of the frame piece, a wedge member on the inner side of the frame piece with its wedging surface directed diagonally towards the inner side 50 of the frame piece and away from its grooved corner edge, and a cooperating wedge member carried by the inner offset margin of the sheet metal section with a similarly inclined wedge surface complementary to that of the wedge member on the frame piece so that thereby

upon relative sliding movement the cooperating wedge members will draw the said angular corners into the respective complementary grooves in firm abutting relation, the said wedge member on the inner side of the frame piece being in the form of an inwardly rounded substantially semi-circular socket with a slotted opening adjacent to the inner side of the grooved edge of the frame piece, and the said cooperating wedge member on the sheet metal section being in the form of an inwardly rounded substantially semi-circularly bent extension from the inner offset margin of the sheet metal section forming a wedge plug which is slidable into the 70 said socket by reason of the said slotted opening therein.

5. The invention defined in claim 1, in combination with cooperating locking members carried by the respective separate parts independently of and separate from the wedge members for holding the latter in firm engagement by preventing sliding disengaging movement thereof.

6. The invention defined in claim 2, in combination with a lug projecting from the said offset inner edge portion of the sheet metal section, a cam member movably mounted upon the inner side of the frame piece to engage with this lug for drawing the wedge members into firm wedging relation, the said cam and lug being separate from the said wedge members, and a projecting finger on the said cam to engage with the said lug in the engaged position of the cam thereby to 100 prevent overthrow of the latter.

7. The invention defined in claim 4, in combination with a hollow vertically channel-shaped lug formed as a bent projection on the inner edge of the sheet metal section to have its open channel side adjacent the inner surface of the frame piece, a rotatable cam pivoted upon the inner side of the frame piece over which cam in its disengaged position the channel-shaped lug may slide as the said wedge plug moves into the said socket in the relative sliding movement of the sheet metal section and the frame piece, the said lug being separate from the said wedge plug, the said cam being shaped to engage with the adjacent end of the said lug to force the plug and socket tightly together in wedged relation, and a projecting finger on the cam to abut against the end of the lug for thereby locking the engaged cam against overthrow.

In witness whereof, I hereunto subscribe my signature.

ANTOINE VÉRICEL.
